UNITED STATES PATENT OFFICE

NORMAN H. SAUNDERS, OF HOMEWOOD, ILLINOIS, ASSIGNOR, BY MESNE ASSIGNMENTS, TO ASSOCIATED ELECTRIC LABORATORIES, INC., OF CHICAGO, ILLINOIS, A CORPORATION OF DELAWARE

ELAPSED TIME METERING SYSTEM

Application filed April 9, 1930. Serial No. 442,829.

The present invention relates to elapsed time metering in general, but is concerned more particularly with elapsed time metering semi-automatic telephone systems, in which calls are extended through the medium of automatic switches controlled from an operator's position.

The principal object of this invention, briefly stated, is the provision of new and improved circuit arrangements whereby a calling subscriber may be charged for all calls, regardless of whether or not those calls are completed, according to the time the calling subscriber's receiver is off of the receiver hook, the charge being assessed at intervals during that time.

A feature of the system, provided in accordance with said principal object, is an arrangement whereby, when a busy condition is encountered at any time during the establishment of the connection, a busy signal is transmitted from the trunk equipment associated with the first switch of the switch train, and whereby all of the switches succeeding the trunk equipment are released for use of other calling subscribers.

Another feature is the arrangement whereby the operator's impulse sender is released, when a busy condition is encountered, without it being necessary for that sender to complete the sending of the remaining digits.

Other objects and features having to do with the refinement of the various circuits peculiar to a system of this character but not being specifically pointed out now, will be readily apparent from a perusal of the description to follow, reference being had to the accompanying drawings comprising Figs. 1 to 5, inclusive, which, when arranged with Fig. 2 to the right of Fig. 1, Fig. 3 directly below Fig. 1, and Figs. 4 and 5 to the right of Fig. 3, show by means of the usual circuit diagrams sufficient of the apparatus employed in a system embodying the principles of the invention to enable a complete understanding thereof to be had.

General description

The equipment shown in Fig. 1 includes the subscriber's station "A", the line of which

terminates at the exchange in the automatic lineswitch C which has access to trunks among which is the trunk comprising conductors 1 to 3, inclusive. Individual to this trunk is a trunk relay group RG and a selector switch D, and it is through this trunk relay group that connection is established between the calling subscriber and the operator, and through which the operator's sending equipment operates the selector D to extend the connection. It is through the relay group RG that the calling subscriber's elapsed time meter M is operated when connection is made with the trunk 1-3 by the subscriber's lineswitch C.

The lineswitch C is mechanically of the well known rotary type in which the wipers have no normal position, remain in the last position in which they were last used, and move in a forward direction only.

The meter M may be considered as representing any of the well known devices whereby the reversal of current through a magnet results in the operation of a registering means. A meter of this type is shown in United States Letters Patent, No. 912,268, issued to Charles M. Beattie, under date of February 9th, 1909.

The selector D is mechanically of the well known vertical and rotary type in which the bank contacts are arranged in horizontal rows or levels accessible to the switch wipers which are carried by the switch shaft, which shaft is elevated in a step-by-step motion in accordance with the impulses received by the selector to position the wipers opposite the corresponding level, and which is then automatically rotated to position the wipers in engagement with a set of contacts in that level associated with an idle trunk leading to the next switch in the train.

Associated with the trunk relay group RG is a sender-selector switch SS, the function of which is to select an idle operator's impulse sender and associate that sender and the operator's telephone equipment with the trunk 1-3.

The apparatus shown in Fig. 2 of the drawings is the connector E and the ringing frequency selector RFS. This connector E

is mechanically the same as the selector D, Fig. 1, except that the switch shaft is directly controlled in its rotary motion, that is, is rotated a number of steps in accordance with the second series of impulses received by the connector. The connector E by being provided with the ringing frequency selector RFS is adapted for use in telephone systems having ten-party lines.

10 The ringing frequency selector RFS is mechanically of the well known rotary type of switch whose wipers have a normal position and are advanced therefrom in a step-by-step motion by the operating magnet 79'. The operation of the release magnet 80' causes the wipers to return to their normal positions.

15 The apparatus represented by the rectangle P, Fig. 1, and the rectangle P1, Fig. 2, may each be considered as a continuously operating device by means of which the polarity of the two associated conductors is reversed at predetermined intervals. As will be more clearly explained hereinafter, the said conductors serve as a source of battery feed for the calling line and in order that there need be no interruptions of the undulatory voice currents which may be traversing the line, the apparatus is arranged to gradually decrease the potential and subsequently increase it gradually to the maximum voltage. A device of this kind is shown in the aforementioned Beattie patent.

20 The apparatus shown in Figs. 3, 4 and 5 includes the operator's sender-control key set and associated relays, and one of four senders. The portion of the sender shown in Fig. 3 includes the relays 111 to 114, inclusive. The registering portion of the 25 sender is shown in Fig. 4, while the sending portion is shown in Fig. 5.

25 The layout of the apparatus is such that each semi-automatic operator's position is provided with four senders similar to that shown in the drawings. The sender-selector SS, Fig. 2, which is usually a 25 position mechanism, has access to senders of several operators' positions.

30 Although the system as shown in the drawings involves the use of only a first selector and a connector, second and even third selectors may be placed between the selector D and the connector E. In that case, selectors like selector D will be employed.

55 *Detailed description*

35 The apparatus having been described generally in this manner, it will now be described in detail as to its operation. For this purpose, it will be assumed that the subscriber at substation A, Fig. 1, desires a connection to be set up from his line to the line of another subscriber, whose number is, for example, 7945, it being remembered that this 40 subscriber is one of ten subscribers who are

on the desired line and whose telephone numbers differ only in the last digit which is the ringing-code selecting digit.

45 When the receiver is removed from the receiver hook at station A, the lineswitch C, the circuits of which are not shown, operates in the usual manner to select an idle trunk, which trunk, it will be assumed, is the one comprising conductors 1-3. When this trunk is seized, battery feed relay 8 of the 50 trunk relay group RG operates over the calling line and at its armature 9 completes the obvious circuit for slow-to-release relay 10. Relay 10 operates when its circuit is closed and at its armature 11 connects ground to 55 the release trunk conductor 3, so as to guard the trunk line from intrusion and to maintain the lineswitch C operated, and at its armatures 12 and 13 connects the "test" wiper of the sender selector SS to the motor 60 magnet MM thereof.

65 The connection of ground to the release-trunk conductor 3 completes the circuit of relay 17 by way of armature 15 and resting contact of relay 14, lower winding of relay 17, armature 13 and make contact of relay 10, interrupter springs of motor magnet MM, and winding thereof to battery. However, if the wipers of the sender selector SS are in engagement with contacts associated with a 70 busy sender, ground will be present on the contacts with which the "test" wiper is in engagement. This ground will short circuit relay 17 before it has had a chance to operate, and will supply direct ground to the 75 motor magnet MM through the interrupter springs thereof.

75 *Sender selection*

80 When direct ground is so fed to the motor magnet MM of the sender selector SS, the motor magnet will operate and advance its wipers into engagement with the next set of contacts of its bank. If the sender associated with this set of contacts is also busy, the test wiper will again encounter ground and the motor magnet will again operate to 85 advance the sender selector wipers into engagement with the next set of bank contacts. This action will continue until the "test" 90 wiper engages a contact to which no ground is connected.

95 Assuming that the trunk line comprising conductors 24 to 28, inclusive, and extending to the sender shown in Figs. 3, 4 and 5, is 100 the one found to be idle, switching relay 17, which is short-circuited as long as ground potential is encountered by the "test" wiper of the sender selector SS, energizes in series with the motor magnet MM. The motor 105 magnet, because of the relatively high resistance of relay 17, does not operatively energize in series therewith.

110 At armatures 18 and 22, relay 17 when so energized connects the "-talk" and "+talk" 115

wipers, respectively, of the sender selector SS to the negative and positive conductors 1 and 2 of the trunk line, thereby extending those conductors into connection with the 5 negative conductor 24 and the positive conductor 25 extending to the selected sender. At armature 19, relay 17 connects the switching conductor and the "switch" wiper to the winding of relay 4. At armature 20, relay 10 17 disconnects the "test" wiper from the junction of the winding of relay 17 and the motor magnet MM, and connects the wiper to ground, thereby placing a guarding and holding potential upon conductor 26. At 15 armature 21, relay 17 connects its upper low-resistance winding in series with its lower high-resistance winding to insure its being held operated. At its armature 23 relay 17 connects the impulse conductor 28 through 20 the "impulse" wiper of the sender selector SS, to the positive line conductor of the selector D.

In the selected sender, relay 111 operates over the grounded release trunk conductor 25 26, and through contacts of relay 112, and at its lower armature disconnects the corresponding test conductor from ground and extends it to the #1 sender connecting relay 108. This is preparatory to enabling the distributor switch DS to stop on a contact associated with the #1 sender and operate the #1 connecting relay 108, so as to connect the #1 sender with the operator's equipment. At its upper armature, relay 111 places 30 ground upon the associated start-operating slow-acting relay 116 through contacts of relays 105—108. Relay 116 closes a circuit for the associated relay 115, which relay operates and starts the hunting action of the distributor switch DS by connecting the test wiper 125 to stepping magnet 124 through the self-interrupting contacts of the stepping magnet. At its two upper armatures, relay 40 115 disconnects common conductors 118 and 119 from the operator's telephone set and connects the conductor 119 through the associated condenser to the differential tone-generating relay 110.

Each time relay 110 pulls up and closes 50 the circuit for its upper winding in parallel with its lower winding, it falls back due to the differential relation between its two windings, thereby generating a tone current which is impressed upon conductor 119 through the associated condenser. This tone current is not sent back to the calling line 55 for the time being.

The test wiper 125 of the distributor switch DS encounters ground potential on the test contacts of each sender not in calling condition owing to the fact that the relay corresponding to relay 111 in each sender not in a calling condition is deenergized and has 60 a ground potential placed upon the corre-

sponding test conductor at its lower armature.

When the wiper 125 of the distributor switch DS arrives on a contact associated with the calling sender, the first contact or 70 the fifth contact, the stepping operation ceases due to the absence of a direct ground potential on the test conductor. A circuit is then closed for relay 108 through the test wiper 125 and the lower armature of relay 75 111 from battery through stepping magnet 124 and the lower contacts of relay 115. Magnet 124 does not operatively energize in series with relay 108 owing to the relatively high resistance of the latter. When 80 relay 108 operates, it connects, at certain of its lower armatures, the six conductors associated with the operator's key-set, to the corresponding conductors of the sender; it closes a locking circuit for itself at its inner lower armature in multiple with the lower contacts of relay 115; it lights the call lamp associated with the operator's key-set at its upper armature; it connects up the conductors 24 and 25 at its intermediate upper 90 armatures to the common conductors 118 and 119; and at its innermost upper armature it opens the circuit of slow-acting relay 116.

During the time required for relay 116 to fall back after its circuit is opened, the tone 95 generated by the differential tone-relay 110 is heard by the calling subscriber who is informed thereby that he may now give the desired number to the operator.

Relay 116 falls back shortly and opens 100 the circuit of relay 115 in addition to stopping the generating of tone current, whereupon relay 115 falls back and connects conductors 118 and 119 to the operator's telephone set. At the time this connection is 105 made, the operator's telephone set is short-circuited by contacts of relay 109, which relay was energized through make contacts of relay 115, so that the charge on the associated talking condenser is equalized with 110 the potential difference across conductors 118 and 119 in order to shield the operator from disagreeable noises in her head set. Relay 109 falls back an instant later and places the operator's telephone set in communicative 115 connection with the calling subscriber.

Registration of desired number

Upon hearing the number desired by the calling subscriber, which number, as hereinbefore assumed is 7945, the operator depresses the digit keys of her key-set corresponding to the respective digits of the number. It will be noted that the four conductors associated with the digit keys are designated A, B, C and D. The operation of a given digit key results in the grounding of one or more of these conductors. As can be seen in reading the drawings, the conductors 125 grounded responsive to the operation of each 130

key have been noted in parentheses above each key.

When the operator depresses the #7 key, the A conductor is grounded, operating relay A1 of the thousands register TH, Fig. 4, relay 127 being operated at this time from the grounded release trunk conductor 26 through contact and armature of release relay 114 and the inner upper contacts of the transfer relay 126. Upon operating, relay A1 locks itself to conductor 123 through transfer relay 126, but relay 126 does not operate until the initial circuit of relay A1 is opened, being short-circuited until this opening occurs when the digit key #7 is released.

When the #7 key is released, relay 126 operates in series with relay A1 (which latter relay remains operated) and at its inner upper armature disconnects the connecting relay 127, whereupon relays A1—D1 are disconnected from the conductors A to D. At its uppermost armature, relay 126 places ground upon conductor 122 through contacts of relay 129, operating relay 113, Fig. 3, to open a point in the switch-through circuit to be hereinafter described and to place a multiple ground connection on release trunk conductor 26 by way of conductor 26'. At its middle upper armature, relay 126 extends a ground potential to the relays of the hundreds register H, operating relay 131 to connect the conductors A, B, C and D to the relays A2, B2, C2 and D2, respectively.

Now, when the operator depresses the #9 key to register the hundreds digit 9, conductor C is grounded, operating relay C2. This relay locks up in series with relay 130 which remains short-circuited as long as the key is depressed and operates as soon as the key is released. Relay 130, in addition to extending a ground potential to the tens register T to cause relay 135 to operate, disconnects relay 131 and places a further multiple ground connection upon conductor 122.

When the tens digit 4 is registered by depression of the #4 key, relays B3 and C3 are operated over conductors B and C, whereupon they lock up in series with relay 134, which relay operates when the key is released and transfers the control to the units register U by releasing relay 135 and operating relay 139. A further multiple ground connection is made to conductor 122 at the upper armature of relay 134.

When the units digit 5 is registered by the depression of the #5 key, relays B4 and D4 operate over conductors B and D and lock up in series with relay 138, which operates when the key is released to open the circuit of relay 139 and place a still further multiple ground connection upon conductor 122.

Transmission of numbers

Having finished setting up the number, the operator depresses the "Start" key, Fig. 3,

whereupon start relay 112 is operated through contacts of relay 108 and through the lower winding of relay 111. Relay 112 closes a locking circuit for itself to conductor 26 at its inner-upper armature, at the same time disconnecting the upper winding of relay 111 from conductor 26. However, relay 111 remains operated through its lower winding until the "start" key is released, whereupon it falls back and opens the circuit of relay 108, at the same time replacing ground on the associated contacts in the bank of wiper 125 of the distributor switch DS. Relay 108 falls back and disconnects wiper 125 from the associated operating magnet, at the same time severing all connections between the operator's common equipment and the sender #1 and closing the associated point in the chain circuit of start relay 116, so as to enable the distributor switch DS to operate again to connect the operator's head set to another sender which may have been taken for use in the meantime.

As a result of the operation of start relay 112, the switch-through circuit to be herein-after described is prepared at the upper armature of relay 112, and at the middle armature thereof ground is placed from the inner contacts of relay 113 upon the start conductor 121 in order to start the stepping action of the counting switch CS, Fig. 5, under the control of the marginal relay 142 associated with the interrupter I.

It may be pointed out at this time that the interrupter I is first started into operation upon the seizure of the sender when the ground potential is placed upon release conductor 26 and consequently upon the conductor 26'. This results in a closure of a circuit through the magnet winding of the interrupter I and through the marginal stepping relay 142 in series. Relay 142 does not operate in series with the magnet winding of the interrupter I. But, upon the energization of this magnet winding, the weighted pendulum is drawn over to the right, short circuiting the magnet winding of the interrupter, whereupon the interrupter magnet de-energizes and the stepping relay 142 energizes. When the pendulum swings to the left, it again includes the magnet winding of the interrupter in circuit, whereupon relay 142 falls back. As the interrupter I continues to operate, the marginal impulse relay 142 is operated each time the pendulum swings to the right, and the interrupter contacts of the interrupter I are opened each time the pendulum swings to the left.

However, the operation of the interrupter I is ineffective and the operation of the stepping relay 142 is ineffective likewise until start conductor 121 is grounded, as before described, upon the depression of the start key by the operator, from which time each deenergization of the stepping relay 142 results in

an operation of the operating magnet of the counting switch CS from conductor 121 through contacts of stop relay 144. The wipers 145 and 146 of the counting switch CS are advanced only upon the back stroke of the operating magnet, and they consequently remain in the position shown upon the first energization of the magnet. When the pendulum of the interrupter I swings to the right and opens the operating magnet circuit by energizing stepping relay 142, the operating magnet of the counting switch CS falls back and advances the wipers 145 and 146 one step, whereupon pick-up wiper 145 encounters a grounded contact, closing a circuit for pick-up relay 143. Pick-up relay 143 operates and prepares a locking circuit for stop relay 144 at its lower armature; places a further multiple ground connection upon conductor 122 at its upper armature; and at its inner-upper armature it removes one ground connection from the outgoing impulse conductor 28, leaving the conductor grounded only through the contacts of the interrupter I. Now, with the circuit in this condition, each time the pendulum of the interrupter I swings to the left, it sends an "impulse" by removing ground from conductor 28 to deenergize the line relay of the selector D, Fig. 1. The operating magnet of the counting switch CS is reoperated by the deenergization of the stepping relay 142, so that each time the pendulum swings to the right relay 142 reoperates and drops back the operating magnet to advance wipers 145 and 146 another step.

When the wipers of the counting switch are advanced again at the end of the transmission of the impulse, wiper 146 encounters the bank contacts in which the first stop conductor terminates, which stop conductor is grounded only in case the digit being transmitted is the digit 1. The digit being transmitted in this case is the digit 7, stored on the thousands register TH, Fig. 4, from which it follows that the #7 conductor is grounded instead of the #1 conductor. The #7 conductor is grounded at this time through the lower armature and resting contact of transfer relay 129, Fig. 4, right-hand armature and make contact of relay A1, inner-right-hand armature and resting contact of relay B2, inner armature and resting contact of relay C1, and inner armature and resting contact of relay D1. That being the case, the sending operation continues and the advance of the counting switch CS continues until seven impulses have been sent by the interrupter I over the outgoing impulse conductor 28. At the end of the seventh impulse, wipers 145 and 146 are advanced again and wiper 146 closes a circuit for stop relay 144 when it encounters the bank contact in which the grounded stop conductor #7 terminates.

Relay 144 operates and locks itself through the lower contacts of relay 143; closes a re-

storing circuit for the counting switch CS at its inner-upper armature; stops the impulse transmission by shunting the sending contacts of the interrupter I at another upper armature; places a further multiple ground connection upon conductor 122 at still another armature; and at its uppermost armature it disconnects the operating magnet of the counting switch CS from the impulse circuit controlled by the stepping relay 142.

Responsive to the closure of the restoring circuit of the counting switch CS at the inner upper contacts of relay 144, the self-interrupting operating magnet of the counting switch operates rapidly in a buzzer-like manner and the wipers 145 and 146 are advanced until they stand in the position shown in the drawings, whereupon the action ceases due to the fact that the normal contact in the bank of wiper 145 is ungrounded. At this time, the circuit of the slow-acting pick-up relay 143 is opened, with the result that the relay falls back shortly and opens the locking circuit of relay 144, which relay shortly falls back to start the transmission of the hundreds digit 9.

When the circuit of stop relay 144 is closed to end the transmission of the thousands digit, a parallel circuit is closed over conductor 120 and through contacts of relay 129 for relay 128, Fig. 4. Relay 128 operates and locks itself to conductor 123 in series with relay 129, which latter relay remains short-circuited until the locking circuit of relay 144 is opened by relay 143, whereupon relay 129 energizes in series with relay 128 and transfers the conductor 120 to relay 132 of the hundreds register H.

The sending operation proceeds for the second digit in the same manner as described in connection with the first digit and is terminated at the end of the transmission of nine impulses upon the energization of stop relay 144 when wiper 146 encounters the bank contact in which the stop conductor #9 terminates. The stop conductor #9 is grounded at this time through the lower armature and make contact of relay 129, through the lower armature and resting contact of relay 133, through the right-hand armature and resting contact of relay A2, through the outer-right-hand armature and resting contact of relay B2, through the outer-right-hand armature and make contact of relay C2, and then through the third right-hand armature and resting contact of relay D2.

Relay 132 is energized at this time in multiple with the stop relay 144 and locks itself in series with relay 133, which latter relay operates, when the circuit of the stop relay 144 is opened, and transfers conductor 120 to relay 136 of the tens register T. The stopping ground potential is shifted at the lower

contacts of relay 133 to the register relay of the tens register.

When the transmission of the tens digit takes place, the operation is the same as described hereinbefore until stop relay 144 operates at the end of the fourth interruption in the outgoing control circuit when wiper 146 of the counting switch CS encounters the bank contact in which stop conductor #4 terminates. Stop conductor #4 is grounded, at this time, through the armature and resting contact of relay A3 and the armatures and make contacts of the operated relays B3 and C3 of the tens register. Relays 136 and 137 are operated in a manner similar to relays 132 and 133 to transfer the control to the units register U.

The transmission of the units digit 5 next takes place and is terminated upon the energization of stop relay 144 at the end of the fifth interruption in the outgoing impulse conductor 28 when wiper 146 engages the bank contact in which stop conductor #5 terminates, stop conductor #5 being grounded at this time through contacts of the non-operated relays A4 and C4 and the operated relay B4 and D4.

Freeing the sender

It will be noted that each of the relays 129, 133, 137 and 141, upon operating, removes ground at one point from the multiply-grounded conductor 122. Now, when relay 141 operates upon the opening of the circuit of slow-acting stop relay 144, when pick-up relay 143 falls back at the end of the units digit, it leaves conductor 122 grounded only at the contacts of stop relay 144. When relay 144 falls back at this time, conductor 122 is ungrounded at all points and relay 113, Fig. 3, falls back as the result. Relay 113 removes ground from the start conductor 121 at its inner armature, and at its upper armature it removes ground from conductor 26', thereby removing ground from conductor 26 at one point, and closes the switch-through circuit through contacts of the operated relay 112 and over conductor 27. This circuit includes the "switch" wiper of the sender selector SS, Fig. 1, armature 19 and make contact of relay 17, and the winding of switch-through relay 4. Relay 4 operates and locks itself to release trunk conductor 3 at its armature 5 and make contact, and at armatures 6 and 7, it disconnects the incoming trunk conductors 1 and 2 from the winding of the battery feed relay 8 and extends them to the corresponding conductors of the connection established through the selector D. As a result of this, battery feed relay 8 falls back and is followed by the falling back of relay 10 and consequently relay 17 to disconnect the wipers of the sender selector SS to free the sender. The established connection is now held up over the line of the substation A.

The falling back of relay 17 results in the removal of ground from the release trunk conductor 26. This results in the deenergization of relay 112, Fig. 3, which is locked up to conductor 26 and the deenergization of relays 126, 128 and 129, Fig. 4, which are locked up to conductor 26 over conductor 123 and through the armature and resting contact of relay 114. As a result of the deenergization of relay 126, relays 130, 132 and 133 of the hundreds register H deenergize and in turn cause the deenergization of the relays 132, 136 and 137 of the tens register T, which is followed by the deenergization of relays 138, 140 and 141 of the units register U. The operation of the interrupter I ceases as a result of the removal of ground potential from conductor 26'.

The sender is now at normal and may be seized again for use in another call.

Selector operation

The operation of the automatic switches employed in establishing the connection in response to the trains of impulses transmitted by the sender over conductor 28 will now be described by first detailing the operation of the selector D in response to the first impulse train. Returning now to the point in the description where the relay 17 first operated to connect up the wipers of the sender selector SS, it will be noted that the connection of the "impulsing" wiper at armature 23 to the positive talking conductor connects ground thereto since conductor 28 is grounded through resting contact and armature of relay 143, Fig. 5. This ground is connected to the winding of line relay 30 of selector D, by way of armature 45 and resting contact of switching relay 41 of the selector. This results in the operation of the line relay 30 and the completion of the circuit of release relay 31 from ground by way of armature 44 and resting contact of switching relay 41 through armature and make contact of line relay 30. Release relay 31 operates, at its armature 32, connects ground to the release trunk conductor 3' and, at its armature 33, opens the release magnet circuit and prepares the impulsing circuit for the vertical magnet 36 through the series relay 34.

Each subsequent removal of ground from conductor 28 by the interrupter I, Fig. 5, as has been explained, results in the deenergization of relay 30 and since, in the assumed case, there are seven momentary removals of ground potential from the conductor 28, relay 30 deenergizes seven times. In so doing, relay 30 completes the circuit for the vertical magnet 36 seven times in series with the slow-to-release series relay 34. Relay 34 operates in series with the vertical magnet 36 upon the first impulse and remains operated through the entire series because of its slow-to-release characteristic. Vertical magnet 36

36, however, follows the impulses and with each operation elevates the wipers 46, 47 and 48 of the selector D one step.

When the switch shaft has been elevated 5 one step, the vertical off-normal springs 37' close and complete the circuit of the rotary interrupter relay 37 from grounded release trunk conductor 3', through make contact and armature 35 of relay 34, closed vertical off- 10 normal springs 37', and thence through the winding of relay 37 to battery. Relay 37 thereupon operates, at its armature 38 prepares the circuit for the rotary magnet 40 and, at armature 39, locks itself through the 15 self interrupting springs of rotary magnet 40 to ground at armature 44 of the switch switching relay 41.

After the seven removals of ground from the conductor 28, there is an interval when 20 no interruptions take place since ground is maintained on conductor 28 by stop relay 144, Fig. 5, during the time the counting switch CS is being returned to its normal position. Relay 30 of selector D remains in its operated 25 position during this interval and series relay 34 releases a short time after the last deenergization of relay 30, at its armature 35 opening the initial energizing circuit of the rotary interrupter relay 37 and connect- 30 ing grounded release trunk conductor 3' to the winding of the rotary magnet 40, where- upon rotary magnet 40 operates and rotates the switch shaft and wipers one step. This operation of the rotary magnet 40 opens the 35 locking circuit of rotary interrupter relay 37, which relay thence deenergizes and opens the circuit of the magnet 40. Further stepping of the wipers 46 to 48 by rotation of the switch shaft is dependent upon the condition of the 40 trunk line with which the wipers are in engagement as a result of the first rotary step.

If the trunk with whose contacts the wipers 46 to 48 are in engagement is busy, ground potential will be upon the test contact there- 45 of and will be connected to the winding of the rotary interrupter relay 37 by way of test wiper 47, armature 43 and resting contact of switching relay 41, self interrupting springs of rotary magnet 40, vertical off-normal 50 springs 37', and thence through the winding of the rotary interrupter relay 37. There- upon rotary interrupter relay 37 operates and at armature 38 again completes the circuit for rotary magnet 40, whereupon the 55 shaft and wipers are rotated another step. It will be noted that, during this time, the circuit of switching relay 41 is complete from grounded release trunk conductor, through the eleventh rotary position contacts 29, wind- 60 ing of relay 41, through self interrupting springs of rotary magnet 40 and vertical off- normal springs 37', winding of relay 37 to battery. However, when relay 37 is in its operated position, the winding of relay 41 is 65 short-circuited from ground by way of arma-

ture 44 and resting contact of relay 41, and armature 39 and make contact of relay 37. Ground potential encountered upon busy test contacts by the test wiper 47 also short-circuits the relay 41 to prevent its operation 70 when relay 37 releases.

Each time the private wiper 47 engages a grounded test contact the relay 37 and consequently the rotary magnet 40 are operated to rotate the wipers into engagement with the 75 next set of bank contacts. This action will continue until wiper 47 engages an ungrounded test contact associated with an idle trunk or until the eleventh rotary step has taken place if all trunks are busy.

Should all of the trunks outgoing from the selector D be busy and the selector advances to its eleventh rotary position, cam spring 29 is moved into engagement with its make contact to complete the circuit of busy relay 80 14 from grounded release trunk conductor 3', cam spring 29 and its make contact, armature 6 and resting contact of relay 4, and winding of relay 14 to battery. Relay 14 thereupon operates and at its armature 15 locks itself to 85 grounded release trunk conductor 3, at the same time opening the circuit of relay 17, which latter relay falls back and disconnects the sender from selector D. Relay 14, at its armature 16, connects the secondary winding of the busy tone transformer T in the substation battery feed circuit so that the calling subscriber is furnished a busy tone to inform him that the desired connection cannot be established at this time.

The disconnection of the sender from the selector D allows the sender to release without having to transmit the remaining impulses. That disconnection also results in the opening of the circuit of line relay 30 of the selector D, which relay then falls back and opens the circuit of release relay 31. Relay 31 falls back after an interval and in so doing completes the circuit of the selector release magnet. The release magnet thereupon operates to restore the selector D in the well-known manner.

For the purpose of this description, it will be assumed that the trunk comprising conductors 52, 53 and 54, which are connected to contacts 49, 50 and 51, respectively, is the first idle trunk to be encountered. When this occurs, relay 41 will no longer be short-circuited and it will operate in series with the rotary interrupter relay 37 over the previously traced circuit. Relay 37, however, because of the relatively high resistance of relay 41 does not operatively energize in series therewith.

Upon the operation of relay 41, the talk- 125 ing conductors of the selector D are connected through to the trunk conductors 52 and 54 at armatures 42 and 45 of relay 41, and the circuit of line relay 30 and release relay 31 are opened at armatures 45 and 44, 130

respectively. The operation of armature 45 extends the impulse conductor through wiper 48 and bank contact 51 to trunk conductor 54 leading to the connector E, Fig. 2, to connect ground to the lower winding of the connector line relay 55. At armature 43, the switching relay 41 connects release trunk conductor 3' through wiper 47 and bank contact 50 to the connector release trunk conductor 53. Relays 30 and 31 deenergize following the opening of their circuits, relay 31 remaining operated for an interval, leaving relay 41 the only relay of the selector D in its operated position.

Connector operation

Line relay 55 of connector E operates when ground is connected to its lower winding over trunk conductor 54 since it obtains battery through armature 59 and resting contact of relay 57. At armature 56, relay 55 completes the obvious circuit for release relay 61, which relay thereupon operates and at armature 62 connects ground to the release trunk conductor 53, thereby connecting ground to release conductor 3' before slow release relay 31 deenergizes. In this manner, relay 41 is maintained operated. At its armature 63, relay 61 connects ground to the common locking conductor 63', at its armature 64 prepares the impulsing circuit for the vertical magnet 83 in series with the slow-to-release series relay 81 by way of resting contact and armature 76 of relay 72 and normally engaged vertical off-normal springs 84, and at armature 65 opens the circuit of release magnet 80' of the ringing frequency selector RFS. Besides preparing the impulsing circuit at armature 64, relay 61 opens the circuit of the connector release magnet 71 at that point.

The connector E is now in readiness to receive impulses from the sender of Figs. 3, 4 and 5. As explained, when the counting switch CS returns to its normal position, the stop relay 144 deenergizes and consequently removes one ground connection from the impulse conductor 28, placing the ground connection to this conductor entirely under the control of the interrupter I. The interrupter I thereupon causes nine interruptions, or nine removals of ground from the conductor 28, as has been explained, to deenergize the line relay 55 of the connector nine times. Each deenergization and following energization of the line relay 55 of the connector results in the transmission of a ground impulse over the previously traced circuit through the series relay 81 and the vertical magnet 83. Relay 81 operates with the first impulse and remains operated throughout the entire impulse series because of its slow to release characteristic. Vertical magnet 83, however, follows the impulses and with each operation thereof elevates the switch shaft, and the

wipers 102 to 104 carried thereby, a corresponding number of steps to place the wipers opposite the ninth level of bank contacts. As the switch shaft is elevated the first step, vertical off-normal spring 84 separates from its contact, allowing the contact 84' to engage the normal contact of spring 84 to transfer the impulsing circuit for the vertical magnet 83 through the armature 82 and make contact of relay 81.

After the nine ground removals from the impulsing conductor and consequently from trunk conductor 54, there is an interval when ground remains connected to conductor 54 during which interval line relay 55 remains in its operated position. Shortly after the transmission of the ninth impulse by relay 55, relay 81 releases and, at its armature 82 and resting contact, transfers the impulsing circuit from the vertical magnet to the rotary magnet 94 and to the slow-to-release relay 84 in multiple.

When the next series of interruptions in the circuit of line relay 55 occurs, which in this case is assumed to be four interruptions, four ground impulses are transmitted over the previously traced impulsing circuit to the rotary magnet 94 and the relay 85 in multiple. Relay 85 operates with the first ground impulse and, because of its slow-to-release characteristic, remains operated during the entire series. Rotary magnet 94 follows the impulses and rotates the switch shaft carrying the wipers 102 to 104 four steps to place those wipers into engagement with the bank contacts 102' to 104' of the desired line. When relay 85 operates, at its armature 86 it removes ground from the conductor 86' for a purpose to be described subsequently, at its armature 87 connects the test wiper 103 to the winding of relay 72 through resting contact and armature 97 of switch-through relay 95, and at armature 88 completes a circuit for itself and a circuit for the rotary magnet 94, which rotary magnet circuit is independent of the off-normal springs and the armature 82 of relay 81.

Should the desired line be busy, ground potential will be present upon the test contact 103' and when wiper 103 is placed in connection therewith, the ground will be connected to the relay 72 over the previously described circuit. Relay 72 thereupon operates and, at its armature 75 and make contact, prepares a locking circuit for itself which will be completed when relay 85 releases an interval after the last impulse; at armatures 73, 77 and 78, completes circuit connections which at this time are without effect; and at armature 74 connects conductor 86' to trunk conductor 52 through armature 58 and resting contact of relay 57, to connect ground to that trunk conductor when armature 86 of relay 85 engages its grounded resting contact upon the restoration of

relay 85. This connection of ground to conductor 52 completes the circuit for relay 14 in the trunk relay group RG, Fig. 1, by way of bank contact 49, wiper 46, make contact 5 and armature 42 of relay 41, armature 6 and resting contact of relay 4 of the trunk relay group RG, and thence through the windings of relay 14 to battery. Relay 14 thereupon operates, and at armature 15, locks itself to grounded release trunk conductor 3 and, at armature 16, connects the secondary winding of the busy tone transformer T in series with the battery feed relay 8, so as to superimpose a busy tone upon the trunk conductors 1 and 2 through the winding of the battery feed relay 8 to notify the calling subscriber at substation A that the desired line is busy.

In completing its locking circuit at armature 15, relay 14 opens the circuit of relay 17, which relay then deenergizes and disconnects the wipers of the sender selector SS from the connector E to free the sender without its having to send the last series of impulses. The disconnection of the "impulse" wiper from the positive talking conductor through the selector, results in the disconnection of ground from the lower winding of the line relay 55 of the connector E, which relay thereupon deenergizes and opens the circuit of the release relay 61, which, after an interval, releases and at its armature 64 and resting contact completes the circuit of the release magnet 71 by way of armature 69 and resting contact of relay 67 and vertical off-normal springs 70. The release magnet thereupon operates and restores the connector switch E to its normal position in the usual manner. The removal of ground from the release trunk conductor 53 by the deenergization of the release relay 61 of the connector opens the circuit of the switching relay 41 of the selector D, which relay thereupon releases and, at armature 44 and resting contact, completes the circuit for the selector release magnet by way of armature and resting contact of line relay 30, armature and resting contact of relay 31, and vertical off-normal springs 33'. The selector release magnet thereupon operates and restores the selector D to its normal position in the well-known manner.

Relays 8, 10 and 14 of the trunk relay group are now the only relays in their operated positions and they remain so as long as the subscriber at the substation A maintains his receiver off the receiver hook.

Assuming, however, that the desired line is idle at the time the connector wipers 102 to 104 are placed in engagement with the contacts 102' to 104' of the desired line, wiper 103 does not encounter ground and no circuit is completed, therefore, for the relay 72. When relay 85 deenergizes after the transmission of the four impulses, at resting con-

tact and armature 87 thereof, the circuit for the upper winding of the switch-through relay 95 is completed from grounded release trunk conductor 53 by way of armature 75 and resting contact of relay 72, thence through the upper winding of the relay 95, to the winding of the cut-off relay of the lineswitch of the desired line by way of armature 87 and resting contact of relay 85, wiper 103, and test contact 103'. The cut-off relay 75 of the called subscriber's lineswitch operates in the well known manner to disconnect the line relay thereof from the line to prevent the operation of that relay should the called subscriber desire to initiate a call before his calling bells have been operated. That cut-off relay also connects ground to the test contact 103' to mark the called line busy to all other connectors, by placing ground on the multiplied test contacts in all the banks 85 thereof.

Relay 95 operates when its circuit is so completed and moves its armatures 96 to 101, inclusive, into their operated positions, thereby, at its armature 98, locking itself through its lower winding to the common locking conductor 63'.

The impulsing circuit in the connector is now connected by way of armature 99 and its make contact to the rotary magnet 79' of the ringing frequency selector RFS. When the next and last series of interruptions occur in the circuit of the line relay 55, five ground impulses are transmitted to the rotary magnet 79' of the ringing frequency selector, and, as a result, the wipers 79 and 80 are stepped into engagement with the fifth set of contacts of their banks. Relay 85 operates in multiple with the rotary magnet 79' to remove ground from conductor 86' so that relay 57, whose circuit is prepared by the off-normal springs 66 of the ringing frequency selector RFS when that switch makes its first step, cannot operate until the impulse transmission has been completed. Now, when relay 85 releases at the end of the impulse transmission, at armature 86 it connects ground to conductor 86' to complete the circuit of relay 57 in series with relay 72. Relay 57 operates when its circuit is so completed, at armature 58 connects the upper winding of the line relay 55 to the trunk conductor 52, at armature 59 disconnects the normal battery connection from the lower winding of the line relay 55, and connects the lower winding to the battery feed device P1, thereby feeding talking battery through the two windings of the relay 55 over the talking conductors 52 and 54. At the same time this takes place, the sender connects ground to the "switch" wiper of the sender selector SS, consequently completing the circuit of the relay 4 which operates, as previously explained, to connect the trunk conductors 1 and 2 over the talking conductors 130

110
115
120
125

of the selector D to the talking conductors 52 and 54 of the connector trunk. This connection of the talking conductors extends the circuit of the battery-feed line relay 55 of the connector E over the calling subscriber's loop, thereby maintaining the relay 55 operated. Relay 57 at armature 60 prepares a circuit for the release magnet 80' of the switch RFS.

10 Relay 72 operates in series with relay 57 and, in so doing, completes the ringing circuit at its armatures 73 and 78, and at armature 77 connects the ring back tone to the trunk conductor 54 by way of armature 101 and make contact of switching relay 95 and normally engaged contacts controlled by armature 93 of relay 89, to inform the calling subscriber that the bells at the called station are now being rung.

20 Since it has been assumed that switch RFS received five impulses and the wipers 79 and 80 are in engagement with their fifth bank contacts, 66 cycle ringing current will be applied to the called subscribers' bells over the negative talking conductor by way of wiper 79 of switch RFS, armature 73 and make contact of relay 72, resting contact and armature 90 of ring cut-off relay 89, armature 96 and make contact of relay 95, line wiper 102, bank contact 102', over the called subscriber's negative line conductor and through the subscribers' calling bells to ground. The 66 cycle ringing current is projected over the just described circuit from superimposed battery of a 66 cycle ringing current generator.

25 The called subscriber hearing the ringing of his bell, removes the receiver from the switch hook and thereby completes the loop circuit over the line terminating in the contacts 102' and 104', thereby completing the circuit for the upper winding of the ring cut-off relay from the superimposed battery, over the ringing circuit just described with the exception of the bells, through contacts controlled by the called subscriber's switch hook, over the positive line conductor, bank contact 104', positive line wiper 104, make contact and armature 100 of relay 95, armature 93 and resting contact of relay 89, make contact and armature 78 of relay 72, wiper 80 of switch RFS, fifth bank contact and jumper to first bank contact, and upper winding of relay 89 to grounded common locking conductor 63'. Relay 89 operates in this circuit, at its armature 91 locks itself up to common locking conductor 63' through its lower winding, and at armatures 90 and 90 opens the ringing circuit and extends the called subscriber's loop to the windings of the back bridge relay 67. At armature 92, relay 89 prepares a substitute locking circuit for itself which will be independent of the armature 63 of release relay 61 when the back bridge relay 67 operates, which it does shortly after the ring cut-off relay 89 operates.

Talking battery is fed through the back bridge relay 37 to the called subscriber, while talking battery is fed to the calling subscriber through the windings of the line relay 55 from the battery feed source P1.

70 Referring now in the sequence of operations to the point where relay 4 operated to extend the calling subscriber's loop through to the connector E, it will be noted that as before explained, the battery feed source P through the windings of relay 8 is disconnected from the trunk conductors 1 and 2 to thereby substitute the battery feed source P1 for the source P. As before explained this disconnection of relay 8 results in the freeing 75 of the sender for use in the extension of other calls.

75 The connection as now described in the trunk relay group, in the selector D, and in the connector E, is maintained as long as the two stations remain in talking connection 80 with each other, and no change takes place until one or both of the subscribers replace their receivers on the receiver hooks.

Release of connection

80 Should the calling subscriber at substation A be the first to replace his receiver upon the receiver hook, the loop circuit over conductors 1 and 2 is opened and consequently 85 results in the release of line relay 55 of the connector E. Relay 55, in releasing, at its armature 56 opens the circuit of release relay 61, which relay after an interval deenergizes 90 and at its armature 62 removes ground from the release trunk conductor 53, thereby opening the holding circuit for switching relay 41 of the selector D. At its armature 63, relay 61 removes one ground connection from holding conductor 63' ground being maintained 95 thereon through armature 68 and make contact of relay 67 and grounded armature 92 and make contact of the ring cut-off relay 89. At its armature 64, relay 61 prepares the circuit for the release magnet 71 of the connector 100 E, the circuit for release of the magnet being maintained open at armature 69 of back bridge relay 67. At armature 65, relay 61 completes the circuit for release magnet 80' 105 of the ringing frequency selecting switch RFS from grounded armature 60 and make contact of relay 57.

110 The completion of the circuit for the release magnet 80' of the switch RFS results in the return of wipers 79 and 80 thereof to their normal position, in which position the switch opens its off-normal contacts 66, thereby opening the series circuit of relays 57 and 72. Relays 57 and 72 thereupon deenergize, and relay 57 at armature 60 opens the circuit of the release magnet 80' of the switch RFS. Further release of the connector E is dependent upon the replacement of the receiver upon the receiver hook at the called station.

In the selector D, relay 41 falls back when ground is removed from the release trunk conductor 53, and, in so doing, at its armature 44 and resting contact completes the circuit of the selector release magnet by way of armature and resting contact of relay 30, armature 33 and resting contact of relay 31, and through vertical off-normal springs 33'. The release magnet of the selector D operates, and, in the well known manner, restores the switch shaft and wipers to their normal position, thereby opening the off-normal springs 33' to open the release magnet circuit.

The removal of ground from the release trunk conductor 53 of the connector E results in the removal of ground from the release trunk conductor 3' and release trunk conductor 3. The locking circuit of relays 4 and 14 are thereby opened and these relays release, restoring the trunk relay group RG to its normal position, or that in which the relays thereof are shown in Fig. 1.

The replacement of the called subscriber's receiver upon the receiver hook results in the opening of the circuit of the back bridge relay 67, which relay thereupon deenergizes and, in so doing, at armature 68, removes ground from the common locking conductor 63', and at its armature 69 and resting contact, completes the circuit of the connector release magnet 71. Relays 89 and 95, which are locked up through their lower windings to the common conductor 63', deenergize as a result of the removal of ground from that conductor.

Release magnet 71 operates, when its circuit is completed at armature 69 and resting contact of relay 6, and in the well known manner restores the connector to its normal position. The equipment is now in readiness to be taken into use for the establishment of another connection.

Ringing source and application

From the connection of the bank contacts of the wipers 79 and 80 of the ringing frequency selector RFS, it will be noted that the sources of the various frequencies of ringing current are selectable to the wiper 79 through the first five contacts of its bank, while those sources are selectable to the wiper 80 through the last five contacts of its bank. Thus, when the ringing-selection digit, or the last digit transmitted by the sender, comprises five or less impulses, one of the five sources of ringing current will be applied to the called subscriber's bells by way of wiper 79 and then over the negative talking conductor. If the ringing frequency digit comprises more than five impulses, the ringing current will be applied over the positive talking conductor to the called subscriber's station by way of wiper 80. This is the well known manner of code ringing in the case of a ten-party-line telephone system.

Metering

When the calling subscriber's lineswitch C finds an idle trunk upon the subscriber at substation A initiating a call, as has been explained, the current for the calling subscriber's circuit is supplied from the battery feed source P. Since, as explained, this source is one which at predetermined intervals reverses the polarity of this current in the calling subscriber's circuit, the operation of the elapsed time meter M is commenced substantially at the time when the calling subscriber removes his receiver from the receiver hook since the hunting time of the lineswitch C is practically negligible. When the desired line is found to be idle by the connector E, the battery feed source P1 is substituted for the source P, and the operation of the elapsed time meter M continues until the calling subscriber replaces his receiver upon the receiver hook.

It will be remembered, that, in the case where the selector D could find no idle trunk leading to a succeeding switch and in the case where the connector E found the desired line to be busy, the relays 8, 10 and 14 of the relay group RG were held operated while the selector D and the connector E were released. That condition resulted in the application of busy tone to the calling subscriber's line by the superimposing of busy tone current upon the current from the source P. Inasmuch as the current from the source P is applied to the subscriber's circuit as long as the subscriber's receiver remains off the hook, the operation of the elapsed time meter M takes place until the subscriber's circuit is opened by the replacement of the receiver on the receiver hook. In this manner the calling subscriber is charged for substantially all of the time his telephone is in use in the establishment of a connection.

When the subscriber at substation A is the recipient of a call, the subscriber's meter is not operated since no current reversals take place over the conductors 1' and 2' inasmuch as the talking current is supplied through the back bridge relay of the connector in use, which relay has its windings connected direct to a constant polarity source as may be seen in the case of the back bridge relay 67 of the connector E.

The invention having been thus described, what is considered new and what is desired to have protected by Letters Patent will be pointed out more specifically in the claims which follow.

What is claimed is:

1. In a telephone system, a calling line terminating in an exchange, a meter for said line, a trunk, means responsive to the initiation of a call over said calling line for connecting said line and trunk together, and

- means responsive to said connection for periodically operating said meter as long as said connection is maintained.
2. In a telephone system, a calling line, a meter therefor, a trunk, a source of periodically pole-changing current, and means responsive to the initiation of a call over said line for connecting said line to said trunk and connecting said current source to said line, said source connected to said line to supply talking current to said line and periodically operate said meter.
3. In a telephone system, a calling line, a meter therefor, a trunk terminating in a selector, a source of periodically pole-changing current associated with said trunk, a plurality of connectors, means responsive to the initiation of a call over said line for connecting said line to said trunk and connecting said current source to said line for periodically operating said meter, means for operating said selector to cause it to automatically hunt for an idle one of said connectors, and means operated by said selector when it finds all of said connectors busy for supplying a busy tone to said line while maintaining the periodic operation of said meter.
4. In a semi-automatic telephone system, a calling line, a meter therefor, a called line, a trunk terminating in a selector, a source of periodically pole-changing current associated with said trunk, means responsive to the initiation of a call over said calling line for connecting said line to said trunk and connecting said current source to said calling line for periodically operating said meter, a connector, an operator's position, means associated with said trunk and responsive to the connection of said calling line with said trunk for connecting said trunk to said operator's position, said current source supplying talking current to said calling line, means associated with said position for operating said selector to extend said calling line to said connector and for thereafter operating said connector to extend said calling line to said called line, a second source of periodically pole-changing current associated with said connector, and means responsive to the extension of said calling line to said called line for transferring the periodic operation of said meter from the first mentioned source of pole-changing current to said second source.
5. In a telephone system, a calling line, a meter therefor, a called line, a trunk terminating in a selector, a connector, means for connecting said calling line to said trunk, means for operating said selector to extend said calling line to said connector and for thereafter operating said connector to connect said calling line with said called line, means associated with said trunk and responsive to the connection of said calling line to said trunk for periodically operating said meter until said calling line is connected with said called line, means responsive to the connection of said calling line with said called line for transferring the operation of said meter to said connector, and means in said connector for thereafter periodically operating said meter.
6. In a telephone system, a calling line, a meter therefor, a trunk, non-numerical means for connecting said line with said trunk, a train of switches accessible over said trunk, means for operating said switches for extending a call from said line, and means responsive to the connection of said line with said trunk for periodically operating said meter as long as said connection is maintained regardless of the success of said train of switches in extending the call.
7. In a telephone system, a calling line, a meter therefor, a called line, a trunk, means responsive to the initiation of a call over said calling line for connecting said calling line with said trunk, means for connecting said trunk with said called line provided said called line is idle, and means for periodically operating said meter responsive to the connection of said calling line with said trunk and for continuing that periodic operation as long as said calling line is connected with said trunk regardless of whether or not said trunk is connected with said called line.
8. In a telephone system, a calling line, a meter therefor, a two section trunk, a first source of periodically pole-changing current normally connected to the first section, a second source of periodically pole-changing current, means for connecting said line with said first section to commence the periodic operation of said meter by said first current source, means for connecting said second current source to the second section of said trunk, and means for disconnecting said first section from said first source and connecting said first section to said second section to transfer the periodic operation of said meter to said second source.
9. In a telephone system, a calling line, a meter therefor, a called line, a two portion trunk terminating in a selector, a first source of periodically pole-changing current normally connected with one portion of said trunk, means responsive to the initiation of a call over said calling line for connecting said calling line with said one trunk portion to thereby connect said first current source to said line for periodically operating said meter, a connector, a second source of pole-changing current associated with said connector, means for operating said selector to extend the other portion of said trunk to said connector and for thereafter operating said connector to extend other trunk portion to said called line, means in

- said connector operating automatically if said called line is idle when said other trunk portion is extended thereto to connect said other trunk portion to said called line and to connect said second current source to said other trunk portion, and means for thereafter disconnecting said one trunk portion from said first source and connecting said one portion to said other portion to transfer the periodic operation of said meter to said second source. 10
11. In a telephone system, a calling line, a meter therefor, a called line, a two portion trunk terminating in a selector, a first source of periodically pole-changing current normally connected with one portion of said trunk, means responsive to the initiation of a call over said calling line for connecting said calling line with said one trunk portion to thereby connect said first current source to said line for periodically operating said meter, a connector, a second source of pole-changing current associated with said connector, means for operating said selector to extend the other portion of said trunk to said connector and for thereafter operating said connector to extend said other trunk portion to said called line, means in said connector operating automatically if said called line is idle when said other trunk portion is extended thereto to connect said other trunk portion to said called line and to connect said second current source to said other trunk portion, means for thereafter disconnecting said one trunk portion from said first source and connecting said one portion to transfer the periodic operation of said meter to said second source, means in said connector for preventing the connection of said other trunk portion to said called line and the connection of said second source to said other portion if said called line is busy, and means responsive to the operation of said preventing means for supplying said calling line with a busy tone while maintaining the periodic operation of said meter by said first source and for causing the release of said selector and connector. 50
12. In a telephone system, a calling line, a meter therefor, a called line, a trunk having a first section and a second section, a first source of pole-changing current normally connected to said first section, a second source of pole-changing current associated with said second section, means for connecting said first trunk section with said calling line to connect said first current source to said calling line to periodically operate said meter, means for connecting said second section to said called line and for connecting said second current source to said second section, and means for disconnecting said first section from said first source and for connecting the two sections together to transfer the periodic operation of said meter to said second source. 70
13. In a telephone system, a calling line, a meter therefor, a first source of periodically pole-changing current, a second source of periodically pole-changing current, means responsive to the initiation of a call over said line for connecting said first source to said line to periodically operate said meter, means for extending the initiated call, and means for thereafter disconnecting said line from said first source and connecting it to said second source to transfer the periodic operation of said meter to said second source. 80
14. In a telephone system, a calling line, a meter therefor, a first source of periodically pole changing current, a second source of periodically pole changing current, means responsive to the initiation of a call over said line for connecting said first source to said line to periodically operate said meter, means for extending the initiated call provided no busy condition is encountered, means operable where the initiated call is extended for disconnecting said line from said first source and connecting said line to said second source to transfer the periodic operation of said meter to said second source, and means for preventing the operation of said last means if a busy condition is encountered, thereby maintaining the periodic operation of said meter by said first source. 90
15. In a telephone system, a calling line, a meter therefor, a line therefor, a meter associated with said line, a trunk having means for periodically operating a meter, means responsive to the removal of the receiver from the receiver hook at said station for connecting said line to said trunk, said means thereupon periodically operating said meter. 100
16. In a telephone system, a calling line, a meter therefor, a trunk having a source of periodically pole-changing current associated therewith, and an automatic switch responsive to the removal of the receiver from the receiver hook at the substation of said line for connecting said line to said trunk and said source of current, said pole-changing current thereupon periodically operating said meter. 110
17. In a telephone system, a calling line, a meter therefor, a called line, a train of switches, a trunk incoming to the first switch of said train, means responsive to the initiation of a call over said calling line for connecting said calling line to said trunk, means associated with said trunk and rendered effective by the connection of the calling line thereto for periodically operating said meter, means for operating the switches of said train successively to extend the call to said called line, and means responsive to the encountering of a busy condition by anyone 120
18. In a telephone system, a calling line, a meter therefor, a called line, a trunk having a first section and a second section, a first source of pole-changing current normally connected to said first section, a second source of pole-changing current associated with said second section, means for connecting said first trunk section with said calling line to connect said first current source to said calling line to periodically operate said meter, means for connecting said second section to said called line and for connecting said second current source to said second section, and means for disconnecting said first section from said first source and for connecting the two sections together to transfer the periodic operation of said meter to said second source. 125

of said switches while attempting to extend the call for supplying a busy tone to said calling line without affecting the periodic operation of said meter.

⁵ In witness whereof, I hereunto subscribe my name this 5th day of April, A. D. 1930.

NORMAN H. SAUNDERS.
